UNITED STATES PATENT OFFICE.

HOMER V. MADDOX, OF LOS ANGELES, CALIFORNIA.

TRAFFIC SIGNAL.

Application filed August 28, 1923. Serial No. 659,812.

To all whom it may concern:

Be it known that I, HOMER V. MADDOX, a citizen of the United States, residing at Los Angeles, in the county of Los Angeles 5 and State of California, have invented certain new and useful Improvements in Traffic Signals; and I do hereby declare the following to be a full, clear, and exact description of the invention, such as will 10 enable others skilled in the art to which it appertains to make and use the same.

The invention relates to vehicular signal devices and has for its object to provide a signal which may be applied to motor 15 driven vehicles of the open or closed type and which may be readily operated by the driver to signal the intention of turning either to the right or to the left, going ahead, stopping or reversing, the construction being 20 such as to admit of the signal being readily installed without requiring any change in the construction or arrangement of parts of the vehicle.

Other objects and advantages will be apparent and suggest themselves as the nature 25 of the invention is understood.

While the drawings illustrate an embodiment of the invention it is to be understood that in adapting the same to meet different 30 conditions and requirements, various changes in the form, proportion and minor details of construction may be resorted to without departing from the nature of the invention.

Referring to the accompanying drawings 35 forming a part of the application:

Figure 1 is a top plan view of a vehicle signal showing the same attached to the standard of the usual windshield, the dotted lines indicating an adjusted position, of the 40 indicating arm and operating handle,

Figure 2 is a detail sectional view on the line 2—2 of Figure 1,

Figure 3 is a detail sectional view on the 45 line 3—3 of Figure 1,

Figure 4 is a detail sectional view on the line 4—4 of Figure 1,

Figure 5 is a detail view of an arrangement adapting the signal to a closed car, and

Figure 6 is a detail sectional view on the 50 line 6—6 of Figure 5, parts being broken away.

Corresponding and like parts are referred to in the following description and designated in the several views of the drawings 55 by like reference characters.

The numeral 1 designates a tube which is adapted to be attached to the vehicle in any convenient and determinate way. The numeral 2 designates a part of the vehicle to which the signal is attached and the same 60 may consist of a standard for supporting the windshield or an upright. An arm 3 is secured at one end to the support 2 and is provided at its opposite end with a bearing 4 in which the tube 1 is mounted, said bearing being split and adapted to be contracted whereby to grip the tube 1 more or less tightly to normally hold the same in the required position and yet admit of said tube being turned in the bearing upon the application of sufficient force thereto. A handle 5 is provided at the inner end of the tube 1 and serves as convenient means for turning the tube when it is required to adjust the same. An elbow 6 is provided at 70 the outer end of the tube 1 and a branch thereof normally extends vertically. A horizontal shaft 7 is mounted in the tube 1 which forms a housing therefor. A shaft 8 perpendicular to the shaft 7 is mounted in 75 a bearing 9 applied to the outer branch of the elbow 6. Bevel gearing 10 connects the adjacent ends of the shafts 7 and 8. The handle 5 is tubular and receives a shaft 11 which is journaled therein and connected at 80 its inner end with the inner end of the shaft 7 by means of bevel gearing 12. A handle 13 is fast to the outer or projecting end of the shaft 11 and when operated effects a turning of the shafts 11, 7 and 8. An indicator 14 is fast to the projecting end of the shaft 8 so as to turn therewith. In the preferable form the indicator 14 has the outline of an arrow, but in practice it may be of any configuration. Lamps 15 are provided at opposite ends of the indicator to render the same plainly visible after dark. These lamps preferably consist of electric 95 bulbs which are included in a circuit represented by the wires 16 in Figure 3. The lamps may be of any preferred color to meet various requirements.

Rotation of the handle 13 effects a corresponding movement of the indicator 14 which may be turned to point to the right 105 or to the left, or forwardly or rearwardly to designate the intention of the driver to turn either to the right or to the left, or to go forward or reverse. Movement of the handle 5 effects rotation of the tube 1 to 110

cause the indicator 14 to point upwardly or downwardly, accordingly as it is the intention of the driver to reverse or stop.

When the signal is applied to a closed car, 5 an arm 17 is clamped to the inner end of the tube 1 and a wire 18 is connected to the outer end of the arm 17 and passes through a guide 19 applied to the support 2 and is provided at its inner end with a button 20 10 which may be conveniently operated from within the car to move the arm 17 and effect a turning of the tube 1.

What is claimed is:

1. In a vehicle signal, a tube, a shaft 15 journaled within the tube, an indicator carried by the tube and geared to said shaft to be operated thereby, means for operating the shaft to effect adjustment of said indicator, a support including a bearing in 20 which the said tube is mounted, means for creating a tension between said bearing and tube whereby to hold the latter in the required adjusted position, a handle project-

ing from the tube and serving as means for turning the same in the adjustable bearing, 25 and means associated with the handle whereby to effect adjustment of the tube.

2. A vehicle signal comprising a tube, elbows at opposite ends of the tube and extending in different directions with respect thereto, means connecting the tube and elbow, a shaft journaled in said means, means operable to rotate the shaft, a handle extending from one of the elbows in which the last mentioned means is disposed, a gearing connecting the last mentioned means with the shaft and located in the last mentioned elbow, a signal supported on the other elbow, a gearing connection from said shaft to the last mentioned elbow to the signal. 30 35

In testimony whereof I affix my signature in presence of two witnesses.

HOMER V. MADDOX.
